CLAIM

The ornamental design for a gas oven range, as shown and described.

DESCRIPTION

FIG. 1 is a perspective view of a gas oven range, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof in an alternate position;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines illustrating portions of the gas oven range form no part of the claimed design.

The dot-dashed broken lines define boundaries of the claimed design and form no part of the claimed design.

1 Claim, 14 Drawing Sheets
